REFRIGERANT DEOILER

Ernest F. Vilter, Milwaukee, Wis., assignor to The
Vilter Manufacturing Company, Milwaukee,
Wis., a corporation of Wisconsin

Application November 15, 1943, Serial No. 510,330

2 Claims. (Cl. 62—115)

1

My invention relates in general to improvements in devices for separating one fluid from another, and relates more specifically to improvements in the construction and operation of apparatus for de-oiling liquid refrigerant or the like.

The primary object of this invention is to provide an improved de-oiler for refrigeration systems or the like, which is simple in construction and efficient in operation.

During prolonged operation of mechanical refrigeration systems the refrigerating medium frequently becomes polluted with excessive quantities of lubricating oil, and the presence of this oil materially decreases the efficiency of the evaporators and of the system in general. In order that the continuity of operation of the refrigerating systems be maintained, any device for effecting removal of the excess oil from the refrigerant, must be adapted to function without seriously interrupting the operation of the system, and while prior attempts at de-oiling such cooling systems have heretofore been made, the prior oil removers were either too complicated and unreliable in action, or they undesirably disturbed the continuity of operation of the systems to which they were applied, or they were relatively inefficient and too difficult to manipulate.

It is therefore a more specific object of the present invention to provide a new and useful refrigerant de-oiling assemblage which besides being extremely simple in construction and highly effective in use, is also reliable in operation and adapted to function without interfering with the normal continuous operation of the refrigeration system with which it cooperates.

Another specific object of my present invention is to provide an improved device for effectively separating and removing liquid such as oil from liquid refrigerant or the like, and for effecting constant delivery of the purified refrigerant to a continuously functioning refrigeration system.

A further specific object of the invention is to provide improved apparatus for rapidly and effectively de-oiling a continuously operating refrigeration system without disturbing its continuity of operation.

Still another object of this invention is to provide a simplified de-oiling system which can be manufactured and installed at moderate cost, and which is conveniently manipulable to produce efficient results.

An additional specific object of my invention is to provide an improved refrigerant de-oiler which is extremely dependable in operation, and wherein some of the refrigerant which is constantly being

2

circulated through a system, is utilized to actually effect the oil separation.

These and other specific objects and advantages of the present invention will be apparent from the following detailed description.

A clear conception of a preferred embodiment of my invention, and of the mode of constructing and of operating a refrigerant de-oiler built in accordance with the improvement, may be had by referring to the drawings accompanying and forming a part of this specification wherein like reference characters designate the same or similar parts of the various views.

Fig. 1 is a central vertical section through a complementary pair or set of interchangeably operable refrigerant de-oiling devices, the section having been taken in the common axial plane of both devices;

Fig. 2 is a similar vertical section through one of the de-oilers, the section having been taken at right angles to that of Fig. 1;

Fig. 3 is a transverse or horizontal section through one of the de-oiling units, the section having been taken along the line 3—3 of Fig. 1; and

Fig. 4 is a diagrammatic perspective view showing the mode of installing a set of the improved de-oiling units in a refrigeration system.

While the invention has been shown and described herein as being especially adapted for the purpose of removing oil from liquid refrigerant in a continuously functioning refrigerating system, it is not my desire or intent to thereby unnecessarily restrict the scope or utility of the improved features some of which may be more generally applicable.

Referring to the drawings, the improved de-oiling device shown therein, comprises in general a pair of similar oil extracting units each of which 40 consists primarily of an outer tubular casing 6; an inner tubular casing 7 of smaller diameter disposed centrally within the outer casing 6 and providing an intervening annular separating space or chamber 8; upper and lower annular end heads 9, 10 respectively, for sealing the adjacent ends of the chamber 8; and a helical cooling coil 11 disposed within the chamber 8 and being spaced from the adjacent surfaces of both casings 6, 7 and maintained concentric with the common 45 casing axis by means of elongated parallel strips 12 secured to the outer surface of the inner casing 7.

The outer and inner casings 6, 7 and the end closure heads 9, 10 and strips 12 of the separating 50 units, may be formed of sheet metal welded or

otherwise united; and while the upper end head 9 of each unit may be disposed perpendicular to the common longitudinal central axis of the two casings 6, 7, the lower end head 10 should be abruptly inclined as shown in Fig. 2. The lowermost portion of the chamber 8 of each unit is provided with an oil drain connection 13, and each of the chambers 8 is also provided with a lower inlet connection 14 and with an upper outlet connection 15 for admitting the oil-laden refrigerant to the chamber and for delivering the clarified refrigerant therefrom. Each of the cooling coils 11 has an upper inlet 16 and a lower outlet 17, and the lower extremity 18 of the outer casing 6 of each unit may be formed so that the units may rest thereon in erect position.

When these improved de-oiling units are utilized in conjunction with a continuously functioning refrigeration system, they are preferably employed in sets or alternately operable pairs, connected to each other and to the piping of the cooling system, and they are also provided with suitable control valves as indicated in the diagram of Fig. 4. In this diagram, the oil drain connection 13 of each unit is provided with an independent drain valve 19, and the lower inlet connections 14 of both units are connected to a common three-way valve 20 which is adapted to interchangeably connect these inlet connections 14 with a warm liquid supply pipe 21 having a stop valve 22 therein. The warm liquid supply pipe 21 is connected at a point between the valve 22 and the valve 20, with another three-way control valve 23 which is adapted to interchangeably connect the supply pipe 21 with the upper coil inlets 16 past independent expansion valves 24 which may be of the thermal type. The upper outlet connections 15 leading from the chambers 8 are cross-connected by a pipe 25 which is communicable with the refrigeration system cold liquid supply pipe 26 past another stop valve 27, and the lower coil outlets 17 are likewise cross-connected by a pipe 28 which communicates with the suction line 29 of the cooling system past still another stop valve 30. All of these three-way, expansion and stop valves may be of standard and well known construction, and the piping system may also be provided with standard unions and other pipe fittings wherever desirable.

During normal operation of the improved de-oiling system, when used in conjunction with a continuously functioning refrigeration system, the two oil removing units are alternately or interchangeably operable, so that one unit is operating to separate the oil from the refrigerant circulating through the cooling system, while the other is simultaneously warming up for discharge of the previously separated oil, and vice versa. Referring to the diagram of Fig. 4, and assuming unit A at the left to be active while unit B at the right is having the previously separated oil drained therefrom, the three-way valves 20, 23 should then be set to cause delivery of incoming oil laden refrigerant from the system to flow only to the left unit A and not to the right unit B. The stop valves 22, 27, 30 should be open, and the drain valve 13 of unit A should be closed. Later on, after the warming up period has terminated, the drain valve of unit B should be slightly open for removal of the excess oil from this unit.

With the apparatus thus set or adjusted, a relatively small proportion of the liquid refrigerant flowing through the supply pipe 21 toward the de-oiling system, will pass through the valve 23 and through the expansion valve 24 of unit A, and

will subsequently gasify and flow downwardly through the cooling coil 11 of this active unit and will thus cool the system chamber 8 of the unit A. The greater portion of the oil laden liquid refrigerant admitted through the supply pipe 21 will however flow through the lower valve 20 and through the lower connection 14 of unit A, and will subsequently fill the chamber 8 and flow upwardly therethrough in intimate contact with the refrigerated cooling coil 11. When the oil laden refrigerant comes in contact with the cold coil 11, the oil is extracted and accumulates in film formation upon this coil, and the relatively pure and cooled liquid refrigerant thereafter flows through the outlet connection 15, cross connection 25, valve 21, and discharge pipe 26 to the refrigeration system for further use. The spent refrigerant within the cooling coil 11 is constantly withdrawn by suction through the lower coil outlet 17, cross connection 28, valve 30 and suction line 29, and this automatic oil removal may be continued until the active cooling coil 11 is well covered with separated oil which will adhere to the coil 11 as long as it is maintained in cold condition.

Since the three-way valves 20, 23 have been set to cause refrigerant to flow only through the coil 11 and chamber 8 of unit A, the inactive unit B will quickly warm up thereby releasing the separated oil which had previously accumulated upon the coil 11 of unit B, and causing this oil to flow by gravity toward the lower outlet 13 of this unit from whence it can be removed by slightly opening the drain valve 19 just before the unit B is again thrown into service. When the unit A has been active for some time and the oil from the unit B has been completely drained, it is a simple matter to cut out unit A and to cut in unit B. This can be done by merely manipulating the three-way valves 20, 23 so as to cause the incoming oil laden refrigerant to circulate through the unit B and not through the unit A, and by closing both drain valves 19. Such interchange of the units A, B can obviously be effected without interrupting the continuity of the refrigerating system to which the de-oiler is applied.

Because of the improved construction of the de-oiling units A, B, the oil separation and removal is thus effected in a most efficient manner. The construction of the casings of these units, with inner and outer walls forming annular chambers 8 the greater portions of which are filled by the large helical cooling coils 11 which however do not touch the surfaces of the adjacent casing walls 6, 7, causes the oil bearing liquid flowing through the chamber 8 to effectively contact the cooled oil accumulation surface, thus insuring rapid and efficient separation of the oil. The elongated spacer strips 12 form simple but effective means for centralizing the coils 11 within the annular chambers 8 and for preventing direct contact between the coils and casings, and the helical formation of the coils 11 compels most of the refrigerant passing upwardly through the chambers to travel along similarly helical paths of great length thus also enhancing the efficiency of the separating units. The provision of outer and inner elongated drums or tubular walls 6, 7 in the formation of the casings, also provides maximum radiation area or surface for warming up purposes.

From the foregoing detailed description of the construction and operation of my refrigerant de-oiler, it will be apparent that the invention pro-

vides an oil removing system which is simple and compact in construction and which is moreover highly efficient in use. The improved apparatus can be readily applied to and used effectively in conjunction with various types of refrigeration systems using liquid refrigerants, without interfering with the continuity of operation of such systems. The improved de-oiling system can also be readily manipulated to rapidly and effectively separate and remove the excess oil, and while conventional manually operable valves have been shown in the diagram, these can obviously be replaced by other types of control valves which would render the system automatic. The improved assemblage has proven highly satisfactory and successful in actual use, and has also proven far superior to any prior known apparatus for like purposes.

It should be understood that it is not desired to limit this invention to the exact details of construction or to the precise mode of operation and use, herein shown and described, for various modifications within the scope of the appended claims may occur to persons skilled in the art.

I claim:

1. A refrigerant de-oiling unit comprising, outer and inner concentric tubular casings forming an intervening upright annular chamber, a helical cooling coil disposed coaxially of and within said chamber and being spaced slightly from the internal surfaces of said walls, valve

means for admitting refrigerant to the upper end of said coil and to the lower portion of said chamber, and valve means for effecting drainage of oil from the lower extremity of said chamber.

- 5 2. A refrigerant de-oiling unit comprising, outer and inner concentric cylindrical casings interconnected and sealed at their adjacent ends to form an intervening annular chamber extending throughout the full length of both casings, a helical cooling coil disposed coaxial of and within said chamber and being spaced slightly from the surfaces of said casings which are exposed to said chamber, valve means for simultaneously admitting refrigerant to the opposite ends of said coil and chamber, and valve means for effecting drainage of accumulated oil from the refrigerant admission end of said chamber.

ERNEST F. VILTER.
